UNITED STATES PATENT OFFICE.

CHARLES F. MERRILL, OF HOPEDALE, MASSACHUSETTS, ASSIGNOR TO DRAPER CORPORATION, OF HOPEDALE, MASSACHUSETTS, A CORPORATION OF MAINE.

METHOD AND APPARATUS FOR FINISHING THE EDGES OF HOLES IN METAL PLATES.

Application filed July 6, 1925. Serial No. 41,696.

This invention relates to an apparatus and a process for the rounding off or the finishing of the edges of circular holes in metal plates. More particularly, the invention is 5 designed for the rounding off or the finishing of the edges of the thread eye holes in steel drop wires such as are employed in the warp stop motions of looms. In such a warp stop motion, each warp is continually 10 reaving through the hole of a drop wire, of which there are a very large number in a loom depending upon the number of ends. If either edge of the hole in the drop wire 15 is rough or sharp, the tendency is to wear, and not infrequently to cut, the warp, thus delaying the weaving operation and requiring the piecing of the warp. These drop wires must be formed rapidly and economically and the hole or thread eye is usually 20 formed by a punching operation, which necessarily leaves the edges in a more or less rough, sharp and unfinished condition.

The object of the present invention is to provide an apparatus and a method by means 25 of which the edges of such holes in such thin, metal plates may be rapidly, economically and uniformly finished so as to present smooth, rounded, convex edges which will not damage or injure the warp passing 30 therethrough.

The nature and objects of the invention will appear more fully from the accompanying description and drawings and will be particularly pointed out in the claims.

The drawings illustrate a simple and practical form of machine or apparatus embodying the invention and designed for carrying out the process of the invention, particularly in connection with the rounding off 35 of the edges of the thread eyes in steel drop wires such as employed in the warp stop motions of looms.

In the drawings:

Fig. 1 is a front elevation of the machine. 45 Fig. 2 is an end elevation looking toward the right of Fig. 1.

Fig. 3 is a top plan view of the machine.

Fig. 4 is a view on a larger scale chiefly 50 in horizontal cross section taken through the axis of one of the spindles and showing the main operative parts.

Fig. 5 is a detail showing the giveway connection between one of the grinding stones and its plunger.

55 Fig. 6 is a face view of a drop wire.

Fig. 7 is a view on a greatly enlarged scale and partially broken away in transverse section showing the general shape of a punched hole in a flat, metal plate or drop wire, the edges of which it is the object of 60 the present invention to finish or round off.

Fig. 8 is a similar view after the left-hand edge has been rounded off in accordance with this invention.

Fig. 9 is a similar view after both edges 65 have been rounded off in accordance with this invention.

Fig. 10 is a similar view showing both edges rounded off on a slightly different contour from that shown in Fig. 9. 70

Fig. 11 is a similar view showing both edges rounded off on still another contour.

Fig. 12 is a view similar to Fig. 8 showing the grinding stone in position at or near the conclusion of the operation. 75

The machine herein illustrated for the purpose of disclosing a preferred embodiment of the present invention and a preferred means for carrying out the process of the invention is of generally square shape. 80 The base 1 has rigidly secured thereto by the bolts 2 the vertical end plate standards 3 and 4, the top edges of which are connected at the front and rear portions by the cover plates 5 and 6, held in place by the 85 screws 7. Vertical, flanged, standard plates 8 and 9 at the front and 10 and 11 at the rear are rigidly secured by the bolts 12 to the cover plates and are in turn connected at the top respectively by the top plates 13 90 at the front and 14 at the rear, these top plates being secured to the top flanges of the standard plates by the screws 15. A pair of tie plates 16 connect the top plates 13 and 14 from front to rear and are secured thereto by the bolts 17. These tie plates in turn are connected by the plate 18, secured 95 thereto by the bolts 19.

The main shaft 20, shown as driven by a pulley 21 from a suitable source of power, 100 extends centrally and transversely through the frame and is supported in bearings formed in brackets 22 and 23 formed on or rigidly secured to the end plate standards 3 and 4, respectively. This main shaft carries a spiral pinion 24 meshing with and driving the spiral gear 25, secured to a vertical shaft 26, mounted at the top in a bearing 27 formed upon or secured to the cover plate 5, and at the bottom in a bearing 28 110

formed upon or secured to a bracket 29, in turn secured by bolts 30 to a flange 31 on the end plate standard 3. This shaft 26 has also secured thereto above the gear 25 the grinder actuating cam 32 and below the gear another cam 33.

A skeleton sliding frame or slide 34, guided at the top in ways 35 formed in the top plates 13 and 14 and the guide arms 36 and 37 projecting respectively forward and rearward therefrom and at the bottom in ways 38 formed in the cover plates 5 and 6 and the guide arms 39 and 40 projecting respectively forward and rearward therefrom, is thus mounted for longitudinal reciprocation fore and aft of the frame. This slide is moved in one direction by a helical spring 41 connected at one end thereto and at its other end to a bracket 42 secured by 20 the bolt 43 to the guide arm 40 and is moved in the other direction by the cam 32 engaging a follower roll 44 journalled on an arm 45 secured to the front end of the slide. This slide carries the grinding stones 46 and 25 47.

The construction of and the means for operating each grinding stone is the same, so that it is sufficient to describe in detail but one, and for convenience the one at the 30 front of the machine is illustrated, particularly in Fig. 4. The slide 34 is formed to present aligned longitudinally supported bearings 48 and 49. These bearings are provided with bushings 50 and in these bushings is rotarily mounted a hollow, cylindrical spindle 51. At the inner end this spindle has secured thereto an apertured cap 52, and at the outer end has threaded thereon another apertured cap 53. A pulley 54 is secured by means of a set screw 55 to the spindle between the bearings 48 and 49. This pulley is driven by a belt from any suitable source of power. The grinding stone 46, which may be an oil stone, is cylindrical in shape representing a pointed end 56, a cylindrical body 57, a cylindrical shank 58, and a wedge-shaped end 59. The shank 58 is somewhat larger than the body 57 forming at their juncture a shoulder 60. The grinding stone fits freely in the hollow spindle 51, so that it may move longitudinally and rotarily therein. Its longitudinal movement inwardly is limited by the engagement of the shoulder 60 with the apertured cap 52, through which the cylindrical body 57 projects. A driving plunger is mounted in the hollow spindle to rotate therewith and slide with respect thereto. This plunger is shown as having a flattened 55 or polygonal shank 61, sliding in a correspondingly shaped aperture in the cap 53 and a head 62 having a V-shaped face to fit over the wedge-shaped end 59 of the grinding stone. A helical spring 63 surrounds the shank of the plunger and is

seated at one end against the head 62 and at the other end against the cap 53. It will thus be seen that the driving plunger acts to force the grinding stone inwardly and also acts to secure the rotation of the 70 grinding stone with the hollow spindle. The wedge-shaped end 59 of the grinding stone and the V-shaped face of the plunger constitute a give-way connection, so that if the grinding stone is prevented from rotation 75 during the operation of the machine, the plunger will yield and rotate with the spindle independently of the grinding stone. As already noted, the construction at the rear of the machine with respect to these elements is the same and comprises a pulley 64, also driven by a belt from a suitable source of power and preferably at the same speed as the pulley 54. Since the spindles carrying the respective grinding stones have 80 fixed longitudinal positions in the slide 34, it will be seen that as the slide is reciprocated by means of the cam 32 and spring 41, the grinding stones are caused to perform 85 their operation alternately.

The flat metal plates constituting the drop wires 65, the edges of the eyes 66 of which this machine is particularly designed to finish or round off, are supported in position for the grinding operation in a rigid supporting guide. This guide is shown as having a head 67 and an upstanding shank 68 adjustably secured by the set screw 69 in a boss 70 on the plate 18. The head 67 is slotted transversely to receive the drop wires 90 and is apertured to allow the passage of the 95 grinding stones.

Suitable means are provided for feeding the drop wires successively into position for the grinding operation. In the construction 105 illustrated, the drop wires are supported in their passage into and out of the machine by a plurality of pairs of grooved feed wheels. Four pairs of such feed wheels are shown. Vertical brackets 71 and 72 are secured by 110 bolts 73 to the top of the cover plates 5 and 6 on each side of the slide 34. The feed wheels 74 of the bottom row are carried by horizontal shafts 75 extending parallel with the axes of the grinding stones and journalled in the brackets 71 and 72. To each shaft is secured a spiral gear 76, held in place by a nut 77. These spiral gears 76 intermesh with complementary spiral gears 78 secured to the main shaft 20, so that all of 115 the lower set of feed wheels 74 are simultaneously driven in the same direction at the same speed. The upper co-operating feed wheels 79 are mounted respectively on shafts 80 arranged above and parallel with the 120 shafts 75 and also having their bearings in the brackets 71 and 72. These upper feed wheels 79 are driven simultaneously and at the same speed with the lower co-operating 125 wheels by means of spiral gears 81 secured 130

to the shafts 80 and meshing with the spiral gears 76. These upper feed wheels have a slight, vertical yielding movement with respect to the lower feed wheels to insure a feeding grip upon the drop wires and to compensate for any slight irregularity in the width of the drop wires. For this purpose the rear ends of the shafts 80 have a loose fit in the brackets 72, while the front ends are journalled in bearing blocks 82 mounted for slight, vertical movement in the bracket 71. These bearing blocks are yieldingly held downwardly by leaf springs 83 secured to the bracket 71 and overlying the bearing blocks. Each shaft 80 is shouldered and the feed wheel 79 and gear 81 are clamped between this shoulder and nut 84 threaded onto the shaft at the rear of the gear.

The drop wires are introduced successively between the feed wheels at the left of the machine and are fed thereby into such a position that the eye to be finished shall stand in axial alignment with the grinding stones or centered in the positioning guide 67. The endwise position of the drop wire is secured by a stop which is withdrawn from position after the grinding operation is completed, so as to allow the continued feeding movement of the drop wires and their discharge from the machine at the right. While a drop wire is thus held stationary for the grinding operation, the feed wheels slip thereon. The stop is shown as a bar 85 guided near its free end in a guide plate 86. This guide plate is adjustably secured to the bracket 71 by means of a clamping screw 87 passing through a slot in the guide plate and threaded into the bracket. The bracket 71 is provided with an aperture 88 to permit the passage of the stop bar 85 therethrough and also a guide arm 89 extending from the guide plate 86, which abuts the end of the drop wire and prevents bending thereof when the stop is withdrawn. The stop is operated in timed relation to the grinding operation and this is conveniently effected by means of the cam 33. For this purpose, the stop bar 85 is pivotally connected at 90 to the arm 91 of a bell crank lever, the pivot of which is a vertical shaft 92 and the other arm 93 of which has pivoted thereon a follower roll 94 engaging the periphery of the cam 33. This shaft 92 of the bell crank lever is pivotally mounted at its upper and lower ends in the arms of a bracket 95 secured to the end plate standard 3 by the bolts 96. A helical spring 97 coiled about the shaft 92 engages at its upper end the bracket 95 and at its lower end the arm 93, and acts to maintain the follower roll 94 in engagement with the periphery of the cam 33.

Means are preferably provided for automatically feeding the drop wires successively

to the feed wheels in timed relation with the grinding operation, and a simple and efficient mechanism for this purpose is illustrated, particularly in Figs. 1 and 3. A bracket 98 is rigidly formed upon or secured to the end plate standard 4 and at the top projects horizontally to the left of the machine. This bracket has secured thereto by bolts 99 a pair of guide arms 100 and 101 projecting toward the front of the machine. A slide bar 102 is mounted in ways in these guide arms and has rigidly secured thereto and extending parallel therewith a trough-shaped holder 103 adapted to receive and support a single drop wire in alignment with the passageway between the feed wheels. A bell crank lever has one arm 104 pivotally connected at 105 to a link 106, in turn pivotally connected at 107 to the slide bar 102. The other arm 108 of this bell crank lever carries a follower roll 109 adapted to cooperate with a cam projection 110 extending downwardly from the lower surface of the cam 33. This bell crank lever is fulcrumed on a shaft 111 mounted in projections 112 extending from the end plate standard 4. A helical spring 113 secured at one end to a lug 114 on the guide arm 100 and at the other end to a projection 115 on the arm 104 of the bell crank lever, tends to hold the slide bar in its retracted position and the follower roll 109 in the path of the cam projection 110. The retracted position of the slide bar 102, and consequently of the trough holder 103, is adjustably determined by a set screw 116 threaded through the end plate standard 4 and engaging the downward prolongation 117 of the arm 104 of the bell crank lever, while the advanced position is determined by the engagement of this arm 104 with a stop lug 118 on the cover plate 5. The drop wires may be fed into the trough holder 103 either by hand or may slide thereinto from a suitable magazine or hopper when the slide bar 102 and trough holder 103 are in the retracted position.

The operation of the machine will be apparent from the foregoing description. With power applied to the main pulley 21 and the grinding stone driving pulleys 54 and 64, at each revolution of the shaft 26 the cam projection 110 will slide the trough holder 103 to deliver a drop wire to the feed wheels 74 and 79; these feed wheels will advance the drop wire until its leading end engages the stop 85, thus positioning it with the eye 66 in axial alignment with the grinding stones and supported in the positioning holder 67; the slide 34 will be reciprocated by the cam 32 and spring 41 first in one direction and then in the other, to cause the grinding stones 46 and 47 to act successively upon, and be withdrawn from contact with, the drop wire in performing the finishing operation; the stop 85 will then be with-

drawn by the action of the cam 33 and the drop wire will then be discharged from the machine by the constantly rotating feed wheels.

5 While this invention is useful for finishing or rounding off the edges of circular holes in plates of metal of various size and quality, it has been particularly designed for use in the finishing of drop wires, and the 10 principles involved are explained particularly in connection with this class of work.

Drop wires themselves vary somewhat in size and shape. An ordinary steel drop wire is about .008 inches in thickness and the diameter of the hole is about .250 inches, so that in illustrating such a drop wire, as in Figs. 7-12 of the drawings, on a large scale, it is necessary to show a considerable portion broken away. The thread eyes 66 are 20 usually formed by a punching operation, so that the peripheral edge 119 at one face of the drop wire presents a fairly smooth convex surface, due to the intrusion of the metal in the punching action, while the peripheral 25 edge 120 at the opposite face is a ragged or uneven and more or less sharp fin, due to the extrusion of the metal in the punching action.

It will be seen, therefore, that if the drop 30 wires were continually presented successively in the same position to the grinding stones, one grinding stone would wear more than the other and the two edges of the drop wires would not be rounded off or finished 35 symmetrically. The process of this invention contemplates, therefore, that the drop wires shall be successively fed into the machine in alternating obverse and reverse positions. This will make the wear on each 40 grinding stone the same and result in symmetrically rounded off or finished edges at both faces of the drop wires.

The action of the grinding stone upon the edge of the hole or thread eye 66 depends 45 chiefly upon (1) the hardness of the metal of which the plates are formed, (2) the condition of the edges of the holes, i. e., whether the edge has a sharp, ragged fin due to the extrusion of the metal, or whether it is 50 comparatively smooth and indented due to the intrusion of the metal by the punching operation, (3) the quality, i. e., the hardness and tenacity of the grinding stones, (4) the rapidity of the cutting action depending 55 upon the speed of the grinding stones and the speed of the feeding movement between them and the plates, (5) the pressure of the grinding stones against the plates and, (6) the excess in the diameter of the cylindrical 60 bodies 57 of the grinding stones over the diameter of the holes themselves.

One of the most important factors in the 65 operation is that last referred to, namely, the diameter of the grinding stones as related to the diameter of the hole to be finished.

It is found in practice that if the thickness of the shoulder on the grinding stone, indicated at 121 in Fig. 12, be about equal to the thickness of the drop wire which means that the diameter of the cylindrical body 57 exceeds the diameter of the hole in the drop wire by twice the thickness of the drop wire, the diameter of the hole will not be materially enlarged in the grinding operation and both edges will be rounded 70 or finished off in flat, smooth, convex curves as shown in Fig. 9. One edge will be finished off, as shown in Fig. 8 with the operation of the first grinder and then the second edge will be finished off to bring the 75 wire into the condition shown in Fig. 9. If this shoulder 121 be increased to twice the thickness of the drop wire, so that the diameter of the cylindrical body of the grinding stone exceeds the diameter of the hole by four times the thickness of the drop wire, a very satisfactory result still ensues, both edges being finished off in wide, flat, 80 convex curves, as shown in Fig. 10. If the shoulder 121 be reduced to one-half the 85 thickness of the drop wire and the cylindrical body of the grinding stone has a diameter exceeding the diameter of the hole by the thickness of the drop wire, then it is found that the grinding operation performed by the first grinding stone removes 90 metal well past the central plane of the drop wire, so that the second grinding stone in its action removes less metal, but by reversing the drop wires, the symmetry of 95 the edges is maintained, but the diameter of the hole or thread eye is enlarged. The result is a finished product substantially as shown in Fig. 11. In practice, therefore, the 100 width of the shoulder 121, under ordinary 105 conditions, should be equal to the thickness of the drop wire and may range from one-half the thickness of the drop wire to twice the thickness of the drop wire and secure 110 satisfactory results. While this range is believed to be the most practical, the invention is not to be understood to be definitely limited thereto.

It is found by correlating the factors named, which may readily be done by controlling the speeds and the width of the shoulder on the grinding stones, that the face of this annular shoulder on each grinding stone will immediately wear into a concavity complementary to the desired convex 115 form of the edge of the hole in the drop wire, and that as the operation proceeds, the face of this shoulder will wear back lengthwise of the grinding stone maintaining this concave shape and thus finishing off the 120 edges of the drop wires with the same concave shape until the grinding stone is worn out by reason of the shoulder 60 coming into contact with the edge of the apertured cap 125 52.

The grinding elements of this invention are designated herein as grinding stones, but this term "stone", in the sense herein used, is to be taken as including natural or artificial abrasives which are stone-like in their character. Such abrasives, when in a form suitable for use in this invention, are more specifically an agglomeration of crystals or sharp particles more or less securely bonded together, as in natural oil stones and cemented compositions, or a spongy, vitreous mass like pumice, as in the case of some of the artificial oil stones.

The essential feature is that the grinding stones, whether of natural or of artificial origin, shall have the qualities necessary to cause them to function in accordance with the principles hereinbefore defined. An oil stone has been found to embody the qualities which permit the application of these principles, but any rigid mass of granular or spongy abrasive material that will wear away by the release of its particles, continually re-forming the shoulder in accordance with the principles of the invention, is a satisfactory grinding stone for the purpose of this invention.

The grinding operation may be performed in the presence of a suitable lubricant which may be supplied in any suitable and usual manner, as, for example, through a pipe 122, so positioned as to discharge the lubricant directly above the hole in the drop wire when positioned for grinding.

Having thus described the invention, what is claimed as new, and desired to be secured by Letters Patent, is:

1. The process of rounding off the edges of similar circular holes in metal plates which consists in simultaneously rotating and forcing into the holes successively, while maintaining it on an axis in alignment with the axis of the hole, a grinding stone having a pointed end and a cylindrical body of such a diameter in excess of the diameter of the hole that the grinding action forms and wears back a uniform, concave, annular shoulder on the stone and in turn forms a corresponding convex edge on the hole of each plate.

2. The process of rounding off the edges of similar circular holes in metal plates which consists in simultaneously rotating and forcing into the holes successively, while maintaining it on an axis in alignment with the axis of the hole, a grinding stone having a pointed end and a cylindrical body of a diameter in excess of that of the holes and in correlating the hardness of the metal of the plates, the condition of the edges of the holes, the hardness and tenacity of the grinding stones, the rapidity of the cutting action, the pressure of the grinding stones against the plates and the excess in the diameter of the cylindrical bodies of

the grinding stones over the diameter of the holes to cause the edges of the holes to be rounded off symmetrically on a convex curve and a uniform, similar, annular shoulder of complementary concavity to be worn back on each grinding stone as the operation proceeds.

3. The process of rounding off the edges of similar punched, circular holes in a series of similar metal plates which consists in presenting the plates successively in alternating obverse and reverse positions with the axes of the holes in substantial alignment with the aligned axes of two oppositely disposed, longitudinally reciprocable and rotatable, similar, pointed, cylindrical, grinding stones having diameters slightly greater than the diameter over all of the metal of the plates extruded and intruded in the punching operation, and in reciprocating the grinding stones while rotating alternately into and out of each hole as presented thereto to cause the edges of the holes to be rounded off symmetrically on a convex curve and a uniform, similar, annular shoulder of complementary concavity to be worn back on each grinder as the operation proceeds.

4. The process of rounding off the edges of similar punched circular holes in a series of similar metal plates which consists in presenting the plates in alternating obverse and reverse positions with the axes of the holes in substantial alignment with the axis of a longitudinally reciprocable and rotatable, pointed, cylindrical, grinding stone having a diameter slightly greater than the diameter over all of the metal of the plates extruded and intruded in the punching operation and in reciprocating the grinder while rotating into and out of each hole as presented thereto to cause the edges of the holes thus presented to be rounded off symmetrically on a convex curve and a uniform, annular shoulder of complementary concavity to be worn back on the grinder as the operation proceeds.

5. A machine for rounding off the edges of similar circular holes in similar metal plates comprising a grinding stone having a pointed end and a cylindrical body of a diameter equal to the diameter of the holes, plus from one to four times the thickness of the plates, and means for simultaneously effecting relative rotation and longitudinal movement successively between each plate and the grinding stone, while maintaining the hole and grinding stone in axial alignment, to cause the edges of the holes to be rounded off symmetrically on a convex curve and a uniform, similar, annular shoulder of complementary concavity to be worn back on each grinding stone.

6. A machine for rounding off the edges of similar circular holes in similar metal

plates comprising a longitudinally recipro-
cable slide, a hollow spindle rotarily
mounted in the slide, means for rotating
the spindle, a cylindrical grinding stone
5 mounted in the spindle to rotate therewith
and slide longitudinally with respect thereto,
means for yieldingly pressing the stone
10 endwise in the spindle, means for feeding
metal plates having similar, circular holes
therein to bring the holes into axial align-
ment with the spindle and for rigidly sup-
porting them when in aligned position, and
means for reciprocating the slide when a
15 plate is in aligned position to force the
grinding stone into yielding engagement
with the edge of the hole to round off the
said edge and then to retract the stone.

7. A machine for rounding off the edges
20 of similar circular holes in similar metal
plates comprising a longitudinally recipro-
cable slide, a hollow spindle rotarily
mounted in the slide, means for rotating
the spindle, a cylindrical grinding stone
25 rotatable and longitudinally slidable in the
spindle and having a shoulder to limit the
projection of its grinding end from the end
of the spindle, a driving plunger mounted
in the spindle to rotate therewith and slide
30 with respect thereto, a spring for yieldingly
forcing the plunger against the rear end of
the grinding stone, a giveaway connection

between the plunger and the stone, acting
in conjunction with the spring to cause the
stone to rotate with the plunger under nor-
mal conditions and to permit non-rotation 35
of the stone with the plunger upon the oc-
currence of an abnormal resistance to the
stone, means for feeding metal plates hav-
ing similar circular holes therein to bring
the holes into axial alignment with the 40
spindle and for rigidly supporting them
when in aligned position, and means for re-
ciprocating the slide when a plate is in
aligned position to force the grinding stone
into yielding engagement with the edge of 45
the hole to round off the said edge and then
to retract the stone.

8. A machine for rounding off the edges
50 of similar circular holes in similar metal
plates comprising a cylindrical grinding
stone, means for rotating the stone, means
for intermittently projecting the stone yield-
ingly in the direction of its axis and for
55 then retracting it, means for successively
feeding metal plates having similar circular
holes therein to bring the holes into axial
alignment with the stone, and means for
rigidly supporting the plates when in
aligned position.

In testimony whereof, I have signed my 60
name to this specification.

CHARLES F. MERRILL.
